ELIAS S. MOORE, OF LYNCHBURG, VIRGINIA, ASSIGNOR TO DRAPER CORPORATION,
OF HOPEDALE, MASSACHUSETTS, A CORPORATION OF MAINE.

SHUTTLE-FEELER THREAD CUTTER AND CLAMP.

Application filed December 3, 1925. Serial No. 72,891.

To all whom it may concern:

Be it known that I, ELIAS S. MOORE, a citizen of the United States, residing at Lynchburg, in the county of Campbell and State of Virginia, have invented an Improvement in Shuttle-Feeler Thread Cutters and Clamps, of which the following description, in connection with the accompanying drawings, is a specification, like characters on the drawings representing like parts.

This invention relates to shuttle feeler thread cutters and clamps whereby the end of the out-going filling is cut and removed from the danger zone of being carried into the shed.

It is now the ordinary practice to provide looms with shuttle feeler thread cutters and clamps, and to cause the shuttle feeler to move into rearward feeling position on call for replenishment of filling. In these cases the parters and clamps are usually mounted on the shuttle feeler, and should the shuttle be found in proper position in the shuttle box, the parter and clamp act to cut and clamp the filling end, and then move the filling end leading from the cloth selvage frontwardly so that it may be later brought into the action of the temple thread cutter.

Feeler thread cutters and clamps as heretofore made have in most instances comprised a movable and a stationary parter mounted on the shuttle feeler and a movable and stationary clamp, and the parts have been held to the shuttle feeler by a bolt, between the head of which and the outside member of the assembled parts, a spring washer has been applied for holding the elements of the thread parter and clamp in laterally cooperative relation.

One of the objects of the present invention is to provide a shuttle feeler thread parter and clamp wherein one of the members shall be constituted as a laterally acting spring interposed between the head of the usual bolt on the shuttle feeler and the adjacent elements of the thread parter and clamp, so that it performs the dual function of a clamp member and a spring washer. This simplifies the construction and avoids the multiplicity of parts that have heretofore been incident to shuttle feeler thread parters and clamps.

In accordance with the present invention, the spent filling end adjacent the inner por-

tion of the shuttle box is cut by the thread 55 parter and is clamped in two places, constituting what may be well termed a "double grip" shuttle feeler thread parter and clamp. The clamping elements are preferably formed of a fixed clamping member and a 60 movable clamping member mounted for movement with the movable parting member, and one of the clamping members is constituted as a spring plate to act as a clamping member and also as a spring washer to 65 hold the parts of the parter and clamp in lateral cooperation.

In the drawings:

Fig. 1 is a perspective view of portions of a loom provided with a shuttle feeler having the present invention applied thereto; 70

Fig. 2 is an enlarged plan view of the end of the shuttle feeler and parts constituting the present invention;

Fig. 3 is a side elevation of the movable 75 member of the thread clamp detached from the other parts;

Fig. 4 is a section on the line 4—4 of Fig. 3, showing more particularly the dished character of the movable clamp; 80

Fig. 5 is a section on the line 5—5 of Fig. 3; and

Fig. 6 is an end view of the parter and clamp showing the thread as having been parted and clamped in two places. 85

The particular character of the shuttle feeler may be as desired, but is herein shown as comprising an arm 1 having a hub 2 which is pivotally mounted upon a bolt 3 carried by a bracket 4 secured to the loom 90 frame. The shuttle feeler 1 has its free end portion provided with the jaws 5 and 6, which may be as usual, and extending laterally from the rear end portion of the shuttle feeler is a stud or bolt 7 on which some of 95 the parts of the thread parter and clamp are mounted, as will more fully appear.

The lay 8 may be of usual construction and is herein shown as provided with the transverse recess 9 into which the rear end 100 portion of the shuttle feeler 1 may pass when the shuttle feeler is moved to rearward feeling position. The lay 8 carries the usual shuttle box 10 for the reception of the shuttle 11, and it will be seen from Fig. 1 that the filling *a* extends from the shuttle or shuttle box opposite the shuttle feeler, so that if the latter be moved into its rearward shuttle

feeling position, the thread *a* will be positioned for the action of the thread parter and clamp.

The means for moving the shuttle feeler into its rearward feeling position is not of the essence of the present invention and the full train of mechanism for effecting this purpose is not herein illustrated and may be of any usual construction. In the present instance the jaws 12 and 13 which are actuated on call for replenishment of filling, contain between them the pin 14 extending from the shuttle feeler, so that on call for replenishment of filling, the shuttle feeler is moved to its full shuttle feeling position, as is well understood by those familiar with looms.

The shuttle feeler has secured thereto a fixed parting blade or cutter 15, and mounted upon the stud or pivot pin 7 is the cooperating movable parter or cutter 16, having the tail-piece 17 which is adapted to be struck by a part carried by the lay as the lay moves forward or as the shuttle feeler moves rearwardly in order to actuate the movable parter to part the thread. The action of the fixed and movable parters is not unlike that now already in common use.

Mounted upon the shuttle feeler is the fixed clamping member 18 which may be secured to the shuttle feeler in any appropriate way, but is herein shown as mounted upon the stud or pivot pin 7, and its front end portion is bifurcated, as at 19, to receive a pin 20 extending through a hole 21 in the movable parter. This manner of assembling the fixed and movable parters and the fixed clamping member is not new except in so far as these parts are coordinated with the other member of the parter, as will now be described.

In shuttle feeler thread cutters and parters of the type described, it is usual to provide a spring of some sort between the head of the bolt or stud 7 and the side of the exterior member of the parter and clamp, to hold the parts in proper collateral position for the performance of their respective functions. In the present instance, however, the spring washer is dispensed with, and the movable clamping member, herein indicated as the plate 22 is pivotally mounted upon the stud or bolt 7 and is hollowed or dished, as indicated more clearly in Figs. 2, 4 and 5. The dished formation of the movable parter member 22 gives to the parting member a flexibility or resiliency, so that when interposed between the head of the stud or bolt 7 and the adjacent members of the thread parter and clamp, the movable clamping member 22 serves the dual purpose of a clamp to clamp the thread and a spring washer to hold the elements of the parter and clamp into laterally associated relation.

The movable member 22 of the clamp is given its movement with the movable member of the thread parter and consequently the present invention contemplates that the movable member 22 of the thread clamp 70 shall be connected for movement with the movable thread parter. As shown in the present instance of the invention, the dished plate 22 has its forward end portion recessed as at 23, forming shouldered portions 24 and 25 which rest upon corresponding portions of the tail-piece 17 of the movable thread parter and serve to connect the movable dished clamping member 22 with the movable parter.

The movable clamping member 22 has the central opening 26, as indicated in Figs. 3, 4 and 5, through which the stud or bolt 7 passes, and the movable clamping member 22 is thus interposed between the head of the stud or bolt 7 and the assembled elements of the parter and clamp adjacent thereto, so that the edge portions 27 of the dished parter member 22 bear upon the face, in this instance, of the fixed clamping member 18, and by tightening the stud or bolt 7 of course the spring action of the dished plate or member 22 may be made more or less energetic in holding the parts of the thread parter and clamp in their lateral operative position.

The flexibility of the member 22 of the clamp is augmented by providing the dished plate constituting the movable member 22 of the clamp with a series of openings 28 which may be disposed about the surface of the dished plate. The number of such openings of course may vary or they might in some cases be dispensed with altogether provided the plate itself is given sufficient lateral flexibility to act as a spring washer to hold the elements of the thread parter and clamp in assembled relation while acting also to clamp the thread.

From the construction described as one good practical form of the present invention, it will be apparent that when the shuttle feeler thread parter and clamp are in their rearward operating position and are closed upon the thread, the thread *a*, as indicated in Fig. 6, will first be clamped between the movable clamping member or dished plate 22 and the fixed clamping member 18, as indicated in Fig. 6, and as the movable cutter 16 moves downwardly, it will also clamp the thread between itself and the side of the fixed clamping member 18; and immediately thereafter part the thread, as indicated in Fig. 6.

The shuttle feeler thread parter and clamp of the present invention is therefore of the double grip type and the two clamping members are relatively movable, one being constituted as a spring plate interposed between the head of the stud or bolt project-

ing from the shuttle feeler and the elements of the parter and clamp, to act as a spring washer in holding the parts in lateral co-operating relation and as a clamp for the parted thread.

When the shuttle feeler thread parter and clamp are moved to their rearward parting position on call for replenishment, the jaws of the parter and clamp are opened, as indicated in Fig. 1, and such opening movement is effected by the usual trip 29 mounted upon the upstanding arm 30 secured to the loom frame or bracket supported thereby. The trip 29 cooperates with the pin 31 to open the jaws of the parter and clamp as it moves to rearward position, but as these parts form no essential part of the present invention and are now well understood, no further description or illustration appears necessary.

What is claimed is:

1. A double grip shuttle feeler thread cutter, comprising in combination, a shuttle feeler having a stud, a fixed and a movable thread cutter mounted thereon, a thread clamp cooperating with the movable thread cutter to clamp the thread, a movable thread clamp movable with the movable thread cutter and constituted as a spring plate interposed between the head of the stud and adjacent parts of the parter and clamp to function both as a thread clamp and spring washer.

2. A double grip shuttle feeler thread cutter, comprising, in combination, a shuttle feeler, a thread parter including a movable member, a thread clamp including a fixed clamping member cooperating with the movable thread parter to clamp the thread, a stud secured to the shuttle feeler, and a movable clamping member constituted as a spring plate mounted on the stud and acting as a spring washer to hold the parts laterally in cooperating relation.

3. In a shuttle feeler thread parter and clamp, the combination of a fixed and a movable parter, a fixed thread clamping member, a movable thread clamping member at the side of the fixed clamping member formed as a spring plate and acting both as a yielding washer to hold the parts in co-operating relation and as a thread clamp.

4. In a double grip shuttle feeler thread parter and clamp, the combination of a shuttle feeler, a fixed and a movable thread parter, a fixed and a movable thread clamp, a stud for the pivotal support of the movable parter and movable clamp, one member of the thread clamp being formed as a dished plate to act as both a spring washer and thread clamp.

5. In a double grip shuttle feeler thread parter and clamp, the combination of a shuttle feeler, a fixed and a movable thread parter, a fixed and a movable thread clamp, a stud for the pivotal support of the movable parter and movable clamp, the movable clamp being formed as a dished plate interposed between the head of the stud and adjacent elements of the parter and clamp to function both as a spring washer and thread clamp.

6. In a double grip shuttle feeler thread parter and clamp, the combination of a shuttle feeler, a fixed and a movable thread parter, a fixed and a movable thread clamp, a stud for the pivotal support of the movable parter and movable clamp, one member of the thread clamp being formed as a dished plate having a series of perforations to increase its lateral resiliency and acting as both a spring washer and thread clamp.

7. In a shuttle feeler thread parter and clamp, the combination of a shuttle feeler, a thread parter mounted thereon, and a thread clamp comprising a dished plate to act both as a spring washer and a thread clamp.

8. In a shuttle feeler thread parter and clamp, the combination of a shuttle feeler, a thread parter mounted thereon, and a thread clamp comprising a dished plate having parts removed to increase its lateral flexibility and cause it to act both as a spring washer and a thread clamp.

9. In a shuttle feeler thread parter and clamp, the combination of a shuttle feeler having a pivot stud, a thread parter having a fixed and a movable member, a thread clamp comprising a fixed and a movable member, the said movable member of the clamp being movable with the movable member of the parter and formed as a dished plate interposed between the head of the pivot stud and the adjacent parts mounted thereon to act as both a spring washer and thread clamp.

10. In a shuttle feeler thread parter and clamp, the combination of the shuttle feeler having a pivot stud, a thread parter having a fixed and a movable member, a thread clamp comprising a fixed and a movable member, the said movable member of the clamp being movable with the movable member of the parter and formed as a dished plate provided with a series of holes to increase its lateral resiliency and interposed between the head of the pivot stud and the adjacent parts mounted thereon to act as both a spring washer and thread clamp.

In testimony whereof, I have signed my name to this specification.

ELIAS S. MOORE.
